UNITED STATES PATENT OFFICE

127,519

DESIGN FOR A DRESS ENSEMBLE

Etta Marcus Horblit, Roxbury, Mass.

Application April 14, 1941, Serial No. 100,377

Term of patent 3½ years

To all whom it may concern:

Be it known that I, Etta Marcus Horblit, a citizen of the United States, residing in Roxbury, county of Suffolk, and State of Massachusetts, have invented a new, original, and ornamental Design for a Dress Ensemble, of which the following is a specification, reference being had to the drawing, forming a part thereof, in which:

Fig. 1 is a front view of a dress ensemble showing my new design.

Fig. 2 is a rear view of the ensemble shown in Fig. 1.

Fig. 3 is a front view of the dress portion of the ensemble as shown in Fig. 1.

Fig. 4 is a rear view of Fig. 3.

I claim:

The ornamental design for a dress ensemble, substantially as shown.

ETTA MARCUS HORBLIT.
